UNITED STATES PATENT OFFICE.

HELENE REID, OF PARKERSBURG, IOWA.

WATERING DEVICE.

Application filed September 27, 1923. Serial No. 665,076.

To all whom it may concern:

Be it known that I, HELENE REID, a citizen of the United States, residing at Parkersburg, in the county of Butler and State of 5 Iowa, have invented certain new and useful Improvements in Watering Devices, of which the following is a specification.

This invention relates to watering devices, and has particular reference to fowl watering devices of the barometric type.

The primary object of the invention is to provide a watering device of the above kind which may be cheaply and easily manufactured, and which embraces the desired qualities of simplicity, durability, and efficiency in operation.

Another object of the invention is to provide a barometric watering device for small chicks, which may be conveniently kept 20 clean and which will not get out of order under ordinary circumstances or conditions encountered during its use.

Other objects will appear as the nature of the invention is better understood, and the 25 same consists in the novel form, combination, and arrangement of parts, hereinafter more fully described, shown in the accompanying drawing and claimed:

In the drawing, wherein similar reference 30 characters indicate corresponding parts throughout the several views:

Figure 1 is a perspective view of a watering device constructed in accordance with the present invention.

Figure 2 is a perspective view drawn on a 35 smaller scale, of the reservoir, and

Figure 3 is a transverse sectional view, partly broken away, of the device shown in Figure 1.

Referring more in detail to the drawing, 40 the invention embodies a reservoir 5 and a pan 6 both of which are constructed in a novel manner from sheet metal so as to be characterized by their extreme durability 45 and simplicity.

The pan 6 is formed of sheet metal with a rim formed of upturned side flanges 7 and end flanges 8, the end edges of which are in contiguous relation. The ends of the end 50 flanges 8 are provided with straps 9 that extend against the outer surfaces of the ends of the side flanges 7 to which they are secured by riveting or the like 10, the joints at the corners of the pan being made water 55 tight by means of solder or the like.

The reservoir 5 is adapted to be received

within the pan 6 and is of such size as to leave a space between the rim of the pan and the ends and sides of the reservoir where the water is exposed for access by the chickens 60 as is well known in connection with watering devices of this type.

The reservoir 5 embodies an elongated tubular body portion 11 that is preferably formed by bending a sheet of metal so that 65 the body portion has a rectangular cross section as shown in Figure 3, the ends of the sheet of metal forming the body portion 11 being overlapped at the bottom of the body portion as generally indicated at 12, and 70 secured together as by riveting or the like as at 13. The four walls of the body portion 11 have outturned flanges 14 upon opposite ends thereof which are of a width slightly less than the width of the flanges 7 75 and 8 of the pan 6, and the ends of the body portion 11 are closed by means of flat sheet metal end walls 15 that flatly engage the outer sides of the flanges 14 and have their edges provided with inturned flanges 16 80 that lie flatly against the inner surfaces of the flanges 14 as shown clearly in Figures 1 and 3. Solder or the like is freely employed at the ends of the body for securing water tight joints between the end walls 15 and the 85 body portion 11.

From the above it will be seen that when the reservoir 5 is placed centrally within the pan 6, the flanges 14 and 16 and the end walls 15 will support the bottom of the 90 reservoir body 11 above the bottom of the pan 6 at an elevation below the upper edges of the flanges 7 and 8 which form the rim of said pan 6. Water is placed within the reservoir 5 through an opening 17 formed centrally in the bottom wall of the body portion 11, which opening is preferably provided by providing mating opposed notches in the overlapping edges 12 of the sheet of metal from which the body 11 is formed. 95 The opening 17 also forms a discharge opening thru which the water passes into the pan 6 when the reservoir 5 is placed within said pan, and it is evident that a water seal is thus had for preventing water overflowing 100 the pan 6. The water is thus maintained at a predetermined level in the pan and is replenished automatically by flowing from the reservoir as the water is used from the pan.

From the above description it will be seen 110 that the device embodies only two separable members, which are of simple, cheap and

durable form, and which will present no objectionable crevices or the like in which dirt may lodge to a disagreeable extent, the parts being thereby easily cleaned, and clogging of the device being rendered practically impossible under ordinary conditions met 5 with in the use of the device.

Minor changes may be made without departing from the spirit and scope of the invention as claimed.

What I claim as new is:

- 10 1. A barometric watering device of the character described comprising a shallow elongated pan, an elongated reservoir adapted to be positioned centrally within the pan for providing a narrow water space between 15 the reservoir and the rim of the pan, said reservoir embodying a body portion of elongated tubular form having outturned flanges upon the ends of the walls thereof, flat end walls disposed against the outer 20 faces of the body flanges and having edge flanges turned inwardly against the inner surfaces of said body flanges, said body being formed of a sheet of metal with its ends overlapped at the bottom of the body, and 25 said ends being provided with mating

notches forming a central opening in the bottom of the body.

2. A barometric watering device of the character described comprising a shallow elongated pan, an elongated reservoir adapted to be positioned centrally within the pan for providing a narrow water space between the reservoir and the rim of the pan, said reservoir embodying a body portion of elongated tubular form having outturned flanges upon the ends of the walls thereof, flat end walls disposed against the outer faces of the body flanges and having edge flanges turned inwardly against the inner surfaces of said body flanges, said body being formed of a sheet of metal with its ends overlapped at the bottom of the body, said ends being provided with mating notches 40 forming a central opening in the bottom of the body, the end walls and the body flanges engaging the bottom of the pan to support the bottom of the body above the bottom of the pan at an elevation below the upper 45 edges of the pan rim.

In testimony whereof I affix my signature.

HELENE REID.
